POWER ELEMENT

John S. Freismuth, Arlington Heights, Ill., assignor to Sterling Automotive Manufacturing Company, Elk Grove Village, Ill., a corporation of Illinois
Filed Oct. 15, 1962, Ser. No. 230,647
8 Claims. (Cl. 73—363.3)

This invention relates to new and useful improvements in force-transmitting devices and is more particularly directed to thermal elements of the type operated by pressure changes of a contained pressure-producing material and which are adapted for use in valves, switches, controls and the like.

Heretofore, difficulty has been encountered in the design of such devices or thermal elements, particularly in the design of sealing means for a diaphragm forming a part thereof which contains the pressure-producing material.

An object of the present invention is to provide a new and improved thermal element.

Another object of the present invention is to provide a thermal element having new and improved sealing means forming a part thereof.

Still another object of the present invention is to provide a thermostatic thermal element or device having an expansible material therein adapted for causing movement of a sealing diaphragm.

A further object of the present invention is to provide a diaphragm of preformed rubber or elastomeric material for use in a thermal element or device.

A still further object of the present invention is to provide a diaphragm of rubber or other elastomeric material which cooperates with other parts of the thermal element to prevent both leakage of the pressure-producing material and introduction of the ambient heat producing medium into the thermal element during operation thereof.

Other objects, features and advantages of the present invention will become readily apparent from a careful consideration of the following detailed description, when considered in conjunction with the accompanying drawings, illustrating preferred embodiments of the present invention, wherein like reference numerals and characters refer to like and corresponding parts throughout the several views, and wherein:

FIG. 1 is an enlarged view in vertical section of a thermal element construction in accordance with the principles of the present invention.

FIG. 2 is an exploded view in section of the thermal element of FIG. 1 illustrating one form of a force-transmitting member found useful in the practice of the present invention.

FIG. 3 is an enlarged view in vertical section of a second embodiment of a thermal element constructed in accordance with the present invention.

FIG. 4 is a view in elevation of another form of a force-transmitting member found useful in the practice of the present invention.

Referring to FIGS. 1 and 2, there is shown a thermal element, generally indicated by the numeral 6, which comprises a cup, container or casing 7 constructed of heat-conductive material, such as brass, a bored plunger or piston guide member 8, a diaphragm member 20, a

2

plug member 10, and a piston or plunger 11 reciprocable in the bore 30 of the guide member 8.

The casing 7 is of general cylindrical configuration and is provided with a sleeve rim 12. The guide member 8 is of stepped external construction and includes an upper section 13 which is of generally cylindrical configuration and which is joined to a frusto-conical or truncated conical portion 14 which carries an outturned annular end flange 15 which is sized to be received by a rim sleeve 12 provided on the casing 7. The rim 12 and the casing 7 are of generally cylindrical configuration, and the rim 12 is bent over to form an annular locking flange 12a which secures the flange 15 of the guide member 8 to the casing 7, to assemble the guide member and casing. During such assembly, the diaphragm member 20 is squeezed between the casing and guide member in a recess 37 formed in the lower surface 38 of the guide member (FIG. 2).

The casing 7 defines a chamber 16 (FIG. 2) which is of a diameter greater than the diameter of the bore 30 and is provided to receive a body of expansible and contractible temperature-responsive material 17, which may be a material, such as paraffin or the thermal materials disclosed in U.S. Patent No. 1,259,846. The chamber 16 and bore 30 are coaxial and the casing 7 has a cylindrical side wall 7a and a bottom wall 7b. The chamber 16 has an open upper end indicated by the numeral 19.

Spanning and closing the upper end 19 of the chamber 16 is the diaphragm member 20 of elastomeric or other rubber-like material. Referring to FIG. 2, the diaphragm 20 is premolded and comprises a central body section 21 and an annular peripheral sealing bead 22. The body 21 is premolded to have a uniform cross-sectional dimension or thickness, and the bead 22 is premolded so that it has an upper portion 23 extending above the upper surface 24 of the body section 21 and a similar lower portion 25 extending below the lower surface 26 of the body section 21.

The rim 12 of the casing 7 has an internal shoulder or surface 27 which is provided with an annular sealing groove 28 for receiving the lower portion 25 of the bead 22 of the diaphragm 20. Similarly, the flange 15 of the guide member 8 is provided with an annular sealing groove 29 in alignment with the groove 28. The groove 29 receives the upper portion 23 of the bead 22 of the diaphragm 20.

The guide member and casing are in axial alignment, when assembled, and the guide member 8 is provided with the bore 30 of lesser diameter than the chamber 16 and is sized to receive the piston or plunger 11. The bore 30 is stepped to provide an annular shoulder 31 which is tapered in cross-section. Above the shoulder 31, the bore section 30a, defined by the upper portion 13 of the guide member 8, is circular and is of a first diameter. The bore 30 diverges at an angle adjacent one end thereof to provide a frusto-conical bore section 30b which defines the shoulder 31 and joins the bore section 30a with a cylindrical bore section 30c which is circular and which is of a second diameter greater than the diameter of the guide section 30a.

The plug 10 is inserted in the bore 30 from the recessed end of the flange 15 and is sized to the bore length so that it extends from the recess 37 of the guide member 8

to a location in the first diameter portion of the plunger 11 above the tapered section 30b of the bore 30 as appears in FIG. 1.

Referring to FIG. 4, the plug 10' may be a cylinder of elastomeric material of a predetermined diameter so that, when it is inserted in the bore 30, in the manner above-described, the plug is squeezed to conform to the contour of the bore 30, as clearly appears in FIG. 1. The plug 10, as appears in FIG. 2, may be premolded to a shape which includes a bottom portion 40 which is cylindrical and of a length predetermined in accordance with the length of the bore 30, a frusto-conical portion 41 sized to the diverging portion of the shoulder 31 of the bore 30 and a second cylindrical portion 42 of a lesser diameter than the portion 40 and sized to the upper portion of the bore.

It will be appreciated that the plug 10 (FIG. 2), or 10' (FIG. 4), has an exterior diameter which will assure that the plug is snugly fitted in the bore 30 and in the position shown in FIG. 1.

At one end, the plunger 11 is bottomed against the flat upper surface of the plug 10 or 10', and the plug is bottomed on the upper surface of the diaphragm 20 inwardly of the bead 22.

In assembling the thermal element 6, the temperature responsive material 17 is first introduced into the chamber 16 defined by the casing 7, as appears in FIG. 2, and then the diaphragm 20 disposed over the material 17 with the bead bottom portion 25 seated in the groove 28 formed in the shoulder 27 of the rim 12. Preferably, the material 17 is provided in the chamber 16 in an amount sufficient that the body portion 21 of the diaphragm 20 rests on the top surface of the material 17.

Next, the plug 10 or 10' is inserted from the flanged end of the guide member into the bore 30. If the plug 10' (FIG. 3) is employed, the plug is forced into the diaphragm to conform to the shape of the bore 30, as clearly appears in FIG. 1. If the plug 10 (FIG. 2) is employed, the preshaped plug will also be press-fitted into the bore 30 and will assume the shape of the bore 30, as viewed in FIG. 1.

The guide member, with the plug 10 or 10' in the bore 30, is placed in the rim 12 in such a manner that the upper portion 23 of the bead 22 seats in the annular groove 29 of the guide member and the recess 37 receives the diaphragm body inwardly of the bead 22. The diaphragm body portion 21 is of greater cross-sectional dimension than the depth of the recess 37 for purposes set forth hereinafter.

With the parts thus assembled, the marginal flange 12a of the rim 12 is bent over and inwardly to clamp the guide 8 and casing 7 together as appears in FIG. 1 to complete the assembly of the thermal element. In so clamping the casing and guide member, the diaphragm body 21 is squeezed between the inner upper surface 49 of the casing rim 12 and the inner lower surface 50 of the recess of the guide member to deform the diaphragm and form a reduced portion or neck 32 connecting the bead 22 to the remainder of body 21 which spans the open end of the chamber 16.

The body portion 21 of the diaphragm which spans the material 17 is of generally uniform thickness after the thermal element is assembled and when the temperature of the material 17 is below its expansion level. The bottom wall 33 of the guide member which is located inwardly of the groove 29, it will be observed, extends radially inwardly a greater distance than the side wall 34 of the casing 7 and, thus, overlies more of the diaphragm body 21 than the side wall 34. As the material 17 expands after its expansive temperature level has been reached, the body 21 of the diaphragm will be caused to move upwardly into the bore 30 of the guide member and will define, in cross-section, an inverted cup-shaped portion (not shown). In changing to the cup-shaped form, the diaphragm body 21 acts against the plug 10 which, in the assembled thermal element, is seated against the top

surface of the diaphragm. The diaphragm tends to force the plug 10 upwardly for movement of a part thereof from the larger diameter section 30c of the bore 30 into the smaller diameter section 30a. In being forced through the diverging portion 30b, the area, A, of the plug is reduced. Since the plug 10 or 10' has a constant volume, V_c , the height, H, of the plug in the smaller diameter portion 30a of the bore must increase in accordance with the general formula $V_c = AH$. Therefore, the length, H, of the portion of the plug 10 in the smaller diameter section 30a of the bore will increase as the plug moves in the bore upwardly in this manner. The plug 10 or 10' imparts motion to the piston 11 which acts against an external force, such as a spring (not shown), to actuate a switch or valve (not shown). The spring (not shown) may be a compression spring which is adapted to return the plunger to its inoperative position shown in FIG. 1, when the expansible material 17 contracts as a result of a reduction in the temperature of the material 17 below the expansion temperature limit of the material.

It will be appreciated that the expansion of the material 17 will cause deformation of the diaphragm body 21, and, in so deforming, the thickness of the portion of the diaphragm body 21 spanning the material 17 will be reduced. Moreover, these deformation forces have a tendency to exert a force on the diaphragm body to pull the body inwardly from between the guide member and casing. However, compression of the bead 22 in the corresponding grooves 28 and 29 prevents such inward movement of the diaphragm and maintains the sealing effect thereof on the casing chamber during distortion of the body portion of the diaphragm by the expansion of the material 17. The flange 8 and shoulder 27 which contact outwardly of the grooves 28 and 29 cooperate with the bead 22 and grooves 28 and 29 to prevent leaking of the ambient heat producing medium into the chamber of the casing. Movement, therefore, of the diaphragm during operation of the thermal element is limited thereby to the area underlying the plug 10, and, thus, the aforementioned movement of the diaphragm is increased and is concentrated in the area underlying the plug 10 so that the movement of the plunger and opening of the valve will occur within a short time after initiation of movement of the diaphragm.

In the embodiment of the present invention appearing in FIG. 3, the casing 7 is provided with an outturned annular flange 52 instead of a rim, such as the rim 12 appearing in FIG. 1. A power element assembly clamping member 54 is provided which is a separate sleeve and which is turned inward at both ends, as at 56 and 58 to assemble the casing 7 and guide member 8. The bead 22 of the diaphragm 20 is compressed in the grooves 28 and 29, the plug 10 or 10' is employed as is the stepped bore 30 of the guide member, as clearly appears in FIG. 3. The operation of this assembly is similar to the operation of the assembly of FIG. 1, above described.

It is preferable to provide a recess 60 in the casing 7 which communicates with the casing chamber at the open end thereof. This recess 60 is preferably tapered in cross-section as at 62 and 63, to facilitate seating of the diaphragm during assembly of the thermal element.

Thus, with the present invention, it will be appreciated that a thermal element having a new and improved sealing arrangement for the force-transmitting member or diaphragm 20 is provided which not only prevents extrusion of the expansible material 17 from the casing, but also prevents introduction of the ambient heat producing medium into the casing 7.

Although various minor modifications of the present invention will become readily apparent to those versed in the art, it should be understood that what is intended to be covered by the patent warranted hereon are all such embodiments as reasonably and properly come within the scope of the contribution to the art hereby made.

I claim:

1. A thermal element comprising: a heat conductive

casing having an axial chamber with an open end, the transverse end wall surface of the casing adjacent the open end of the chamber having a sealing groove therein formed inwardly of the outer marginal edge of said end wall surface, a guide member having an axial bore of lesser diameter than the diameter of the chamber and having a transverse end wall surface overlying and extending radially inwardly toward the longitudinal axis of the casing a distance greater than the said end wall of the casing, said end wall surface of the guide member having a counterbore recess formed therein radially inwardly of the outer marginal edges of each of said end wall surfaces, said end wall surface of the guide member having a sealing groove formed in the counterbore recess thereof which is in axial alignment with said sealing groove of the casing; an elastic diaphragm spanning the open end of the chamber and extending between said end wall surfaces of said casing and guide member, said diaphragm including a pre-formed body portion disposed in the counterbore recess of the guide member, said body portion being of uniform cross-sectional dimension which is greater than the depth dimension of said counterbore, and an elastic bead carried at the outer marginal edge of said diaphragm body in both of said sealing grooves, a plunger in the bore of the guide member movably responsive to movement of said diaphragm, and means for clamping said casing and guide member to assemble the thermal element by contacting said end wall surfaces of the casing and guide member outwardly of the bead, whereby said bead is squeezed in said grooves and a portion of the diaphragm body located inwardly of the bead is squeezed between the counterbore portion of the guide member and the end wall surface of the casing to thereby seal the open end of the chamber of the casing.

2. The thermal element of claim 1 wherein said clamping means is a ring.

3. The thermal element of claim 2 wherein said ring is a sleeve which is formed integrally with the casing and which receives the counterbored end wall of the guide member, the sleeve having the outer edge portion thereof turned to clamp the guide member to the casing.

4. The thermal element of claim 2 wherein the ring is a separate member receiving both the casing and the guide member, and wherein opposite ends of the ring are turned to clamp both the guide member and the casing.

5. A thermal element comprising: a heat conductive casing having an axial chamber with an open end, the transverse end wall surface of the casing adjacent the open end of the chamber having a sealing groove therein formed inwardly of the outer marginal edge of said end wall surface, a guide member having an axial bore and an abutting end surface with a sealing groove formed therein which is spaced inwardly of the marginal edge of the abutting end surface and which is in axial alignment with the sealing groove of the casing, said surface of the guide member also having a counterbore therein concentric with the bore; an elastic diaphragm spanning the open end of the chamber and including a pre-formed body disposed in the counterbore, said body portion being of uniform cross-sectional dimension and of greater thickness than the depth of the counterbore, an elastic bead carried by the body at the outer marginal edge thereof, said bead being disposed in both of said sealing grooves, a plunger in the bore of the guide member movably responsive to movement of said diaphragm, and means for clamping said casing and guide member to contact said abutting end surfaces outwardly of the grooves, whereby said head is squeezed in said grooves and the portion of the diaphragm body located inwardly of the bead is squeezed between said abutting end surfaces to thereby seal the open end of the chamber.

6. A thermal element comprising: a heat conductive casing defining a chamber having an open end for receiving a heat responsive expansible material and having an

abutting end wall surface with a sealing groove therein spaced inwardly of the marginal edge of said surface, a guide member having an axial bore and an abutting surface with a sealing groove therein spaced inwardly of the marginal edge of said surface of the guide member and in axial alignment with the sealing groove of the casing, a counterbore in said surface of the guide member concentric with the bore, a movable piston in the bore of the guide member, a resilient diaphragm having a pre-formed body portion of uniform cross-sectional dimension disposed in the counterbore, said body portion being of greater cross-sectional dimension than the depth of the counterbore, a bead having a greater cross-sectional dimension than said body portion carried by the body portion of the diaphragm at the marginal outer edge thereof, said bead being disposed in both of said sealing grooves, and means for clamping said guide member and casing to contact said abutting surfaces of the casing and guide member together with a predetermined applied force to assemble said thermal element, whereby said bead is squeezed in said grooves and a portion of the diaphragm located inwardly of the bead and between the abutting surfaces is squeezed between said surfaces to seal the open end of said casing chamber.

25. 7. A thermal element comprising: a heat conductive casing defining a chamber having an open end for receiving a heat responsive expansible material, a radial outward flange on the casing adjacent the open end of the chamber having an abutting surface with a sealing groove

30. therein spaced inwardly of the outer edge of the flange and carrying a clamping sleeve spaced outwardly of the sealing groove, a guide member in the sleeve having an axial bore and a recess concentric with the bore in a first surface thereof, said first surface having a sealing groove

35. formed in the recessed portion thereof, inwardly of the outer edge of the first surface, and in axial alignment with the sealing groove of the casing, a movable plunger in the bore, a diaphragm having a pre-formed body portion of uniform thickness greater than the depth of the counter-

40. bore disposed in the counterbore of the guide member in contact with the plunger and closing the open end of the chamber, said diaphragm carrying a marginal sealing bead of greater thickness than the body portion, said sealing bead being disposed in the sealing grooves of both the

45. guide member and casing, whereby clamping of said ring with a predetermined applied force to assemble said casing and guide member will squeeze the sealing bead in said sealing grooves and squeeze the portion of the diaphragm body disposed between said abutting surface of the casing flange and the first surface of the guide member to thereby seal the chamber.

50. 8. A thermal element comprising: a heat conductive casing defining a chamber having an open end for receiving a heat responsive expansible material, a radial outward flange on the casing adjacent the open end of the chamber, said flange having an abutting surface with a sealing groove therein spaced inwardly of the outer edge of the flange, a clamping ring carried by the casing outwardly of said groove, a guide member having a bore and

55. carrying an axially extending sleeve in the ring, said sleeve having an abutting surface in surface-to-surface contact with the abutting surface of the casing flange, said sleeve defining with a first surface of the guide member a counterbore concentric with said bore, said first surface of the

60. guide member having a sealing groove therein spaced inwardly of the sleeve and in axial alignment with the sealing groove of the casing, a movable plunger in the bore, a diaphragm having a pre-formed body portion of uniform cross-sectional dimension greater than the depth of the counterbore disposed in the counterbore of the guide member, in contact with the plunger, and closing the open

65. end of the casing, said diaphragm carrying at the marginal edge thereof a sealing bead which is of greater thickness than the said body portion and which is disposed in the

sealing grooves of both the casing and the guide member, whereby clamping of said ring with a predetermined applied force to assemble said casing and said guide member will contact said abutting surfaces of the casing and the guide member flange extending outwardly of the grooves, and cause squeezing of the diaphragm bead in said sealing grooves and of that part of the body portion of the diaphragm which is inwardly of the bead and is located between the abutting surfaces of the guide member and the casing flange to thereby seal the open end of said 10 casing chamber.
